UNITED STATES PATENT OFFICE.

MCLEOD THOMSON, OF CHELSEA, NEW JERSEY, ASSIGNOR TO THE RAIL JOINT COMPANY, OF NEW YORK, N. Y., A CORPORATION OF NEW YORK.

RAIL JOINT.

Application filed August 17, 1928. Serial No. 300,324.

This invention relates to an improvement in rail joint structures, and primarily has in view a novel relation of the joint bar to the rail to obtain to some extent the advantages 5 of the head-free type of rail joint originating in the Thomson Reissue Patent No. 15,773, dated Feb. 19, 1924, and particularly to prevent the undesirable "cocking" inwardly of a bar when worn, and compelling an old 10 joint bar to be straightened to proper fishing position when drawn to a fit by the joint bolts.

To that end, the invention has in view an improvement in rail joints wherein the joint 15 bar at its head has a pivotal action on spaced apart bearing surfaces, and a rotative movement over the rail base around a center in the head of the bar, whereby proper and adequate adjustment may be made by the tightening of 20 the bolts.

It is proposed by the present invention to provide a joint bar which takes a bearing on the rail inwardly of the outer side of its head in such a way that as wear increases, 25 the top surface of the bar is moved further away from the underside of the rail head as the base of the bar is drawn inwardly by the tightening of the bolts. This construction is 30 advantageous because it prevents the "cocking" inwardly of the bar with its resulting disadvantages of improper fit and inefficiency.

A further object of the invention is to provide an improved structure which maintains 35 freedom or clearance of the inner part of the head of the bar from the head fillet in the rail as distinguished from the head fillet engagement of the head-free type of bar covered by the Thomson reissue patent referred 40 to, while at the same time insuring loading engagement for the bar adjacent to the head fillet of the rail with all of the attendant advantages of a loading engagement at or near that point.

45 While the invention is susceptible of various forms of structural embodiment, certain preferred forms are shown in the accompanying drawings, in which:

Figure 1 is a vertical half-sectional view 50 illustrating the preferred form of the invention.

Fig. 2 is a view similar to Fig. 1, illustrating another form of bar embodying the invention.

55 Fig. 3 is a vertical half-sectional view, il-

lustrating the use of a single shim for providing a rail-web bearing for the inner side of a worn bar head.

Fig. 4 is a view similar to Fig. 3, illustrating the use of double shims for the purpose indicated in connection with Fig. 3.

Fig. 5 is a side elevation of one form of shim that may be used.

Fig. 6 is an end elevation of the shim shown in Fig. 5.

Similar reference characters designate corresponding parts throughout the several figures of the drawing.

In carrying the present invention into effect, the same may be embodied in a joint bar 70 of any conventional type, the only requirement being that the joint bar employed shall have its head formed or shaped to provide two bearing surfaces which respectively have a pivoting or sliding engagement with the underside of the rail head and on the rail-web, or its equivalent, adjacent the head fillet.

According to a primary form of the invention shown in Fig. 1 of the drawings, the joint bar 1 having the head 2 and foot flange 3 is provided with the usual openings in its web 1^a to receive the bolts 4 for holding and adjusting the bar on the rail. The bar head 2 is formed at its inner side to provide the spaced rail engaging bearing portions or surfaces A and B, while the outer portion of its upper surface C is formed to maintain at all times a head clearance from the underside of the rail head in the manner of a head-free rail joint. In this embodiment of the 90 invention, it is therefore proposed to modify a head-free bar by providing points of bearing engagement with both the web and the underside of the rail head adjacent to but spanning the head fillet F of the rail head. As wear occurs and the bolts 4 are tightened, the foot flange 3 of the bar will have an inward and upward movement over the rail flange thereby providing the rotative movement of the lower portion of the bar, while the bearing portions A and B at the head of the bar will have a pivoted and sliding engagement on the underside of the rail head and on the rail-web w. It will be seen that in this form of bar, the head thereof has a two point engagement with the rail, namely, with the upper part of the web and the underside of the rail head inwardly from the outer edge thereof, but spanning the fillet of the rail head to avoid head fillet engagement.

100
105
110

As will also be observed from Fig. 1 of the drawings, the outer bolting face 5 of the joint bar may embody the feature of having the outer bolting face of the bar initially inclined downwardly and outwardly from a vertical plane as and for the purposes shown in my former Patent No. 1,650,551, November 22, 1927, although, the invention is equally applicable to a bar having an entirely vertical or non-inclined bolting face as shown in Fig. 2.

In the forms of the invention so far described, the joint bars embody the preferable feature of having direct contact between the inner part of the bar head and the rail. However, to illustrate the range of modification of the invention, Figs. 3 and 4 illustrate the use of shims or spacing plates to provide a solid metal-to-metal engagement of the inner side of the bar head with the rail-web.

This phase of the invention is particularly useful and applicable in connection with a worn bar in which the outer portion of its top bearing surface has been worn down because of the "cocking" inwardly of the bar through wear or faulty application. A bar so worn when restored to its original fishing position, that is, when "straightened up", is spaced from the rail-web at its inner side and has a head clearance to a greater or less degree from the outer portion of the underside of the rail head as will be seen by reference to both Figs. 3 and 4 of the drawings. By using the shims or spacing plates with a worn bar of that kind it may be given the solid metal engagement with the rail-web and with the inner portion of the underside of the rail head, adjacent the head fillet so that it will act in the same manner as and fulfill the functions of a bar integrally formed to have these spaced apart points of engagement with the rail as shown in Figs. 1 and 2. Likewise the adjustment of a bar shimmed to have a position as shown in Figs. 3 and 4 will be inwardly at the base as hereinbefore described.

Referring more in detail to the construction shown in Figs. 3 and 4, wherein the invention is embodied in the continuous type of joint bars, it will be observed from Fig. 3 that the web *w*' of the rail *R* has in contact therewith a spacing plate or shim 6. This shim is normally supported on the top of the joint bolts and extends upwardly into the recess of the head fillet of the rail whereby the inner side 7 of the head 8 of the continuous bar 9 takes a bearing against the shim or spacing plate 6, while the upper edge 10 of the bar head also takes a bearing against the underside of the rail head inwardly from the outer edge thereof. Thus, in this adaptation of the invention the head of the joint bar has a dual engagement with the rail, one engagement being direct, while the other is accomplished through the medium of the

shim 6, thereby accomplishing the same objective as heretofore described.

As previously indicated, the purpose of using shims or spacing plates is to convert old rail joint structures into the present invention, and therefore when using some old bars which have become worn more than others, it is desirable to utilize shims or spacing plates of various thicknesses so that the inner face of the head of the bar may be properly spaced from the rail-web. Accordingly, as will be observed from Fig. 4 of the drawings, a shim 6^a of added thickness may be used between the inner face 7^a of the head 8^a of the bar 9^a and the rail web. It will be observed from Figs. 5 and 6 that the shim 6^a has portions 6^b of added thickness.

When using the shims 6 and 6^a in connection with old or even new joint bars in the manner explained it prevents the "cocking" inwardly thereof, and when using the same in connection solely with worn or old joint bars it strengthens them up to their work. These shims may extend the full length of the joint, although in practice it may be advantageous to use four shims instead of two.

From the foregoing, it will be apparent that in all forms of the invention the essential feature thereof is preserved. That is to say, regardless of whether the invention is used in connection with new or worn bars, the feature of providing a dual engagement at the inside head of the bar is preserved so that the inside corner of the bar does not engage the head fillet of the rail, but on the contrary spans such fillet to provide for the progressive movement of the bars under wear and adjustment by the rocking inward of the lower portion of the bar over the rail flanges, the rocking occurring about the points of dual engagement.

Without further description, it will be understood that changes in the form, proportion and minor details of construction may be resorted to without departing from the spirit or sacrificing any of the advantages of the invention.

I claim:

1. A rail joint structure including the rails, and a splice bar having spaced head bearing surfaces respectively at opposite sides of the head fillet of the rail and having a clearance from the outer portion of the head fishing surface of the rail.

2. A rail joint structure including the rails, and a splice bar having the head thereof provided with spaced bearing surfaces respectively engaging the underside of the rail head and the rail-web and having a clearance from the outer portion of the head fishing surface of the rail.

3. A rail joint structure including the rails, and a splice bar having the head thereof formed for dual engagement with the rail, said points of engagement being respectively

- above and below the head fillet of the rail and having a clearance from the outer portion of the head fishing surface of the rail.
4. A rail joint including the rails, clamping bolts, a splice bar having head-fishing clearance from the outer portion of the underside of the rail head and a loading engagement with the rail at opposite sides of the fillet thereof.
5. A rail joint including the rails, clamping bolts, a splice bar having head clearance from the outer portion of the underside of the rail head and also having spaced bearing surfaces at its upper, inner corner for spanning the head fillet of the rail.
6. A rail joint including the rails, clamping bolts, and a splice bar having head-fishing clearance from the outer portion of the underside of the rail head, and an inner head projection provided with spaced bearing surfaces spanning the head fillets of the rails and having an upwardly sliding bolt tightening engagement with the rail at opposite sides of each fillet.
7. A rail joint including the rails, clamping bolts, and a splice bar having head-fishing clearance from outer portion of the underside of the rail head and a dual engagement with the rail head at opposite sides of the head fillet.
8. A rail joint structure including the rails, and a splice bar having spaced head bearing surfaces respectively at opposite sides of the head fillet of the rail and having a clearance from the outer portion of the head fishing surface of the rail, and a shim plate arranged between one of said bearing surfaces and the rail. 35
9. A rail joint structure including the rails, and a splice bar having spaced head bearing surfaces respectively at opposite sides of the head fillet of the rail and having a clearance from the outer portion of the head fishing surface of the rail, and a shim plate arranged between one of said bearing surfaces and the rail-web. 40
10. A rail joint including in combination, the rails, clamping bolts, a splice bar having head clearance from outer portion of the underside of the rail head and also having spaced bearing surfaces at its upper, inner corner, and a shim plate arranged between one of said bearing surfaces and the rail-web, said bearing surfaces of the splice bar head bearing against the shim plate and the underside of the rail head at opposite sides of the major portion of the head fillet of the rail. 50

In testimony whereof I hereunto affix my signature.

McLEOD THOMSON.
